UNITED STATES PATENT OFFICE.

LANSING ONDERDONK, OF NEW YORK, N. Y., ASSIGNOR TO THE UNION SPECIAL SEWING MACHINE COMPANY, OF CHICAGO, ILLINOIS, A CORPORATION OF ILLINOIS.

TRIMMING DEVICE FOR OVERSEAMING AND OTHER SEWING-MACHINES.

No. 802,587.

Specification of Letters Patent.

Patented Oct. 24, 1905.

Application filed February 18, 1902. Serial No. 94,590.

To all whom it may concern:

Be it known that I, LANSING ONDERDONK, a citizen of the United States, residing at New York, in the county of New York, State 5 of New York, have invented certain new and useful Improvements in Trimming Devices for Overseaming and other Sewing - Machines, of which the following is a description, reference being had to the accompanying drawings and to the letters and figures of reference marked thereon.

The present invention relates to an improvement in trimming devices for sewing-machines, the especial object of the invention being to provide a trimming device for use in connection with machines for overseaming or finishing the edges of knit goods, the trimmer acting in advance of the stitch-forming mechanism to prepare the edge for 20 the reception of the binding-strokes.

As herein shown, my improved trimmer is applied to a machine such as illustrated in my application for Letters Patent filed June 4, 1901, Serial No. 63,078; but it will be understood that I do not wish to be limited to 25 its application to that machine alone, but is applicable to other types of sewing-machines.

The invention consists in the matters hereinafter described, and referred to in the appended claims.

The invention is illustrated in the accompanying drawings, in which—

Figure 1 is a front elevation, partly in section, of a sewing-machine embodying my invention. Fig. 2 is a rear elevation of the same. Fig. 3 is a top plan view, partly in section, with the bed-plate removed, of a sewing-machine embodying the invention. Fig. 4 is a perspective view of the trimmer-40 supporting bar in its relation to the other parts of the sewing-machine mechanism. Fig. 5 is a perspective view of the cloth-plate and throat-plate, showing also the guide for deflecting the trimmed-off strip, the stationary blade coöperating with the movable blade, and the opening for the passage of the lint. Fig. 6 is a detail view, partly in section, showing the mechanism for operating the trimmer. Fig. 7 is a similar view showing 45 the trimmer thrown out of action. Fig. 8 represents detached parts of the mechanism for throwing the trimmer into and out of action.

In the drawings, A represents the bed of a sewing-machine embodying my invention; 55 B, the gooseneck; C, the needle-lever; D, the needle-bar; E, the belt-wheel; F, the eccentric connecting-rod; C', the needle-lever extension; G, the driving-shaft; a, the looper, and X the spreader or looping-hook operated 60 from the needle-lever extension C' and carrying a loop of needle-thread from beneath the work-plate out into position to be engaged by the looper.

As above stated, the present invention 65 pertains particularly to the trimming mechanism, in which 9 represents the upper or movable trimmer-blade, which coöperates with the stationary blade 10, preferably adjustably secured to the bed-plate beneath 70 the throat-plate or with a portion of it extending above the cloth-plate to guide the upper blade in its descent. This lower blade 10 is, as above stated, secured to the bed-plate below the throat-plate 11, which latter 75 is of the shape shown in Fig. 5, having a depressed portion 12, a body portion 7, an opening 8 for the passage of the looper from below up over the edge of the fabric, and the usual openings for the feed-dog and a tongue 80 14, over which the stitches are formed.

The cloth-plate slide 17 is provided with an adjustable guide 15 to deflect the trimmed-off strip away from the needle and an opening 16, through which the lint is carried off. 85

Below the throat-plate and attached to the bed-plate is a plate 5, having a downwardly-turned corner 6.

The upper blade 9 of the trimmer is adjustably secured by the screw 18 to the 90 curved arm 19, which at its lower end below the bed-plate of the machine has a sleeve 20, clamped to a rock-shaft 21, journaled in bearing-lugs 22. Slight play is given the rock - shaft 21, and an adjustable screw-threaded sleeve 23, arranged on the end thereof and having a head 24 bearing against the coiled spring 25 around the shaft, regulates the tension of the spring, which spring keeps the knife when in operative position 100 in bearing-contact with the lower stationary knife, the two blades coöperating to produce the trimming action, and by manipulating the adjustable sleeve 23 wear of the upper blade may be taken up. Projecting from 105 the sleeve 20 is a boss or projection 26, to

which one end of the torsion-spring 27 is attached, the other end being secured to the machine-frame, this spring aiding or tending to swing the arm 19 to release the blade 9 from operative engagement with the blade 10 when the trimmer-operating mechanism, which I am about to describe, is released.

Upon the driving-shaft G is an eccentric 28, which rotates between the flat faces 29 of the fork-piece, these flat pieces 29 being secured together and to the two separated arms or blocks 30, which are loosely sleeved on the rock-shaft.

The screws 31, which hold the flat pieces 15 to the blocks, serve also the purpose of taking up the wear on the fork-piece embracing the eccentric. As the main shaft rotates the fork-piece will vibrate up or down loosely on the rock-shaft 21.

20 In order to oscillate the rock-shaft and through it the trimmer-blade 9, I provide a mechanism to throw the rock-shaft into rigid engagement with the fork-piece, as shown in Figs. 6, 7, and 8. This mechanism 25 comprises an arm 32, fixedly clamped on the rock-shaft 21 between the sleeve 30 and formed at its outer end, as at 33, to be clamped and held in position by the latch 34, pivoted to the forked piece, preferably normally drawn inwardly by the spring 35. A thumb-piece 36 on the latch enables the operator to throw the latch out of engagement with the arm 32, allowing the latter through the spring 27 to be drawn out of engagement 30 with the oscillating fork, thus allowing the latter to oscillate freely on the rock-shaft 21. It will be noticed that when the upper trimmer-blade-supporting member is forced down into co-operative relation to the 40 lower stationary blade 10 the arm 32 will also be forced down, and the end 33 of said arm is so formed that it will force the latch to one side, and then the spring will draw it so that its upper end 37 will clamp the arm 32 and 45 hold the fork-piece and arm 32 rigidly together, and in the oscillation of the fork-piece the upper trimmer-blade will also oscillate.

Having thus described my invention, what I claim, and desire to secure by Letters Patent, is—

50 1. The herein-described trimming device for sewing-machines, comprising an upper trimmer-blade-supporting member, and means for oscillating the same comprising a driving-shaft, a vibrating arm operated thereby, a second arm connected to and movable with the trimmer-blade-supporting member, and a pivoted hooked catch carried by one of said arms and adapted when the upper trimmer-blade is moved into operative 55 position with respect to the lower trimmer-

blade to automatically engage and lock the said second arm and vibrating arm rigidly together; substantially as described.

2. The herein-described trimming device 65 for sewing-machines, comprising an upper trimmer-blade-supporting member, and means for oscillating the same comprising a driving-shaft, a vibrating arm operated thereby, a second arm connected to and movable with the trimmer-blade-supporting member, and a pivoted hooked catch carried by one of said arms and adapted when the upper trimmer-blade is moved into operative position with respect to the lower trimmer-blade to automatically engage and lock the said second arm and vibrating arm rigidly together, and means for raising the upper trimmer-blade out of operative engagement with the lower blade when the catch is 70 released; substantially as described.

3. A sewing-machine trimming device, comprising a rock-shaft, a trimmer-knife-supporting arm secured thereto, two arms extending forwardly from said rock-shaft, 85 one fixed thereon and one pivoted thereto, connections between the pivoted arm and the driving-shaft of the machine, and a pivoted spring-catch normally engaging the fixed arm and holding it in locked connection with the loose arm, and means for throwing the fixed arm and trimmer-knife out of operation when the catch is released; substantially as described.

4. A trimming device for sewing-machines 95 comprising a rock-shaft to which the knife-supporting arm is fixed, a member pivotally attached to said rock-shaft, and operatively connected with the driving-shaft, a second member fixed to said rock-shaft, and a catch 100 pivoted to the pivoted member and normally engaging the fixed member, whereby said members are normally interlocked, and a spring for raising the knife-supporting arm when the catch is released; substantially as 105 described.

5. A trimming device for sewing-machines, comprising a rock-shaft, a knife-supporting arm fixed thereto, a forked arm loosely pivoted upon said rock-shaft, with connections between the same and the driving-shaft, a second arm fixed to the rock-shaft and spring-held out of engagement with the pivoted arm and a catch for holding the fixed arm against the pressure of the spring in engagement with 115 the pivoted arm; substantially as described.

In testimony whereof I affix my signature in presence of two witnesses.
